UNITED STATES PATENT OFFICE

JOHN A. SMITMANS, OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA

BILLET MANIPULATOR FOR ROLLING MILLS

Application filed August 2, 1928. Serial No. 382,887.

My invention pertains to the rolling mill appliances commonly known as manipulators, that is to say, devices for adjusting the ingot, slab, billet, bar, or other metal to be operated on in a rolling mill, on the feed table so as to bring it into proper position for entering the desired pass of the reducing rolls. The invention relates especially to manipulators which function not only to adjust the metal laterally on the feed table but also to tilt the metal to turn it about its longitudinal axis so as to rest on a different edge from theretofore.

Manipulators of the general character to which my invention pertains usually comprise a pair of side guides, one disposed at each side of the feed table of the rolling mill, which are selectively movable so as to direct the metal to the desired pass of the reducing rolls, and also include tilting devices, ordinarily associated with one of the side guides, which are adapted to engage the metal from beneath adjacent one edge so as to raise one side of the metal and tilt the latter about its longitudinal axis. By reason of the heavy work they are called upon to perform, the heat to which they are subjected, the grit, scale and other wear-producing substances to which their moving parts are to a certain extent exposed, etc., these manipulators are required to meet exceptionally hard service conditions. Where bearings requiring accuracy of alignment have been employed for supporting rotating or sliding members, as has been the case in numerous constructions of manipulator heretofore proposed, particularly in connection with the tilting element of the device, much trouble has been experienced by reason of loss of such alignment, resulting from heat and the wear of the moving parts as well as from the shocks and pressures to which such parts are subjected. Difficulties of the same general nature have arisen, also, where, as has sometimes been the case, it has been proposed to employ, for operating the tilting elements of the device, parts which move in planes disposed at angles, generally right angles, with respect to the planes of movement of the parts which operate the

side guides. Attempts have been made to overcome these troubles by mounting a prime source of power (such as an electric motor) for the tilting elements in association with one of the side guides, so as to move with the latter; but such constructions have drawbacks peculiar to themselves. 55

It is one of the objects of my invention to provide a manipulator in which such drawbacks as the above-named will be avoided and which, while being capable of retaining its full working efficiency in spite of the hard service conditions under which it operates, will not necessitate any prime source of power being supported on any moving element thereof and will occupy a minimum of floor space. Other objects of my invention, among which is the provision of a manipulator which is exceptionally economical to build and install, will appear from 60 the following specification taken in connection with the claims annexed thereto. 65

By way of example, I have described in the following specification, and shown in the accompanying drawings, together with a modification thereof, one form of manipulator in which my invention may be embodied. However, I wish it understood that the invention can be embodied in other forms, and that changes can be made in the 70 form described and shown, and in its modification, without exceeding the scope thereof, as defined in the appended claims. 75

In the drawings:

Fig. 1 shows, in plan, the feed table of a 80 rolling mill, having a manipulator constructed in accordance with my invention operatively associated therewith;

Fig. 2 is a sectional elevation on an enlarged scale, the section being taken on the 90 line II—II of Fig. 1;

Fig. 3 is a fragmentary front view on the same scale as Fig. 2, showing a portion of one of the side guides, and one of the lifting fingers associated with the latter, as seen 95 from the line III—III of Fig. 1;

Fig. 4 is a section taken on the line IV—IV of Fig. 2; and

Fig. 5 is a sectional elevation, of the same general nature as Fig. 2, but showing a 100

modified means for actuating the lifting fingers.

Referring now to Figs. 1 to 4, the reducing rolls of an ordinary rolling mill are indicated at 10, and the rolls of an ordinary feed table at 11, the side frames of the feed table being designated 12. Beneath the feed table are arranged suitable support rolls 13 upon which are mounted, so as to be capable of longitudinal movement, a pair of large bars 14 which are formed at their outer ends with upwardly extending heads 15 having plates 16, which constitute what may be termed the outer side guide, secured thereto.

Mounted upon other rolls, similar to the rolls 13, are a second pair of large bars, 17, having at their ends upwardly extending portions 18 to which brackets 19 are connected. These brackets have portions constituting heads 20 in which are formed vertical slots 20a for receiving the lifting fingers 21 to be described below. The heads 20 have secured thereto plates 22 which constitute what may be termed the inner side guide. For shifting the metal transversely of the feed rolls 11, so as to position it to enter the desired pass of reducing rolls, the outer side guide and inner side guide are selectively moved transversely of the feed rolls by means of the bars 14 and 17, respectively.

In order to actuate the bars 14, to obtain the requisite movements of the outer side guide, such bars have racks 23 secured beneath the same, at their inner ends, with which racks mesh pinions 24 carried by a shaft 25 mounted in bearings carried by a suitable foundation, and adapted to be rotated, through a reduction unit 26, from an electric motor 27. Holddown rolls 13a, mounted in stands 18b and engaging the bars 14 from above, are provided for maintaining the racks in proper meshing engagement with the pinions 24. Likewise, the bars 17 have secured beneath the same, at their inner ends, racks 28, with which mesh pinions 29 carried by a shaft 30 which is driven, through a reduction unit 31, from a second electric motor 32. Hold-down rolls 13b, similar to the rolls 13a employed for the bars 14, are provided for the bars 17.

The circuits for the motors 27 and 32 are arranged so that the operation of these motors is selectively under the control of an operator of the mill, in such manner that either motor can be caused to rotate in either direction at will. By this means, either or both of the side guides can be shifted laterally of the feed rolls 11 so as to move the metal into the requisite position on such feed rolls for entering the desired pass of the reducing rolls.

The lifting fingers 21 are formed with hook portions 33, which may be stepped,

as at 34 (Figs. 2 and 3), so that the lifting engagement of the hooks with the metal will occur adjacent the edge of the latter. The lifting fingers are vertically movable in the slots 20a, of the head 20, and, when depressed, occupy such a position that the engaging portions of the hooks 33 are somewhat below the level of the tops of the feed rolls 11, so as to be out of the path of the metal on such feed rolls.

For raising and lowering the lifting fingers 21, the latter are slotted, at 35, to receive the ends of levers 36, which are pivoted at their outer ends in such slots and are secured, at their inner ends, to a pair of separated shafts 37 rockably mounted in bearings 38 carried by the bracket 19. From this it will be seen that when the shafts 37 are rocked in a clockwise direction (Fig. 2), the lifting fingers 21 will be raised to an extent which is determined by the amount of the rocking movement of the shafts. Prior to such raising, the inner side guide 20 will be in proximity with the metal, having, if necessary, been moved into such proximity by operation of the motor 32. Accordingly the stepped engaging portions 34 of the hooks 33 of the lifting fingers will engage beneath the metal, adjacent the edge of the latter, and will tilt the metal as indicated at b in dotted lines in Fig. 2. Having been thus tilted, the metal can be further manipulated, by pushing it laterally with either or both of the side guides, until it rests upon an edge other than that upon which it was previously resting.

For actuating the shafts 37 to rock the same, these shafts have secured, to the ends thereof which are adjacent each other, a pair of levers 39 between which is pivoted the enlarged head 40 of a bar 41, so that a reciprocation of such bar will effect a rocking of the shafts 37 in one direction or the other. The shafts 37, bar 41 and other associated parts of the lifting fingers, all move with the inner side guide during the various adjustments of the position of the latter; and it is necessary that the movement of the side guide shall not result in any material movement of the lifting fingers with respect thereto. In order to maintain this condition, and at the same time provide for actuating the lifting fingers 21 when desired, the bar 41 has secured beneath it, at its inner end, a rack 42 with which meshes a pinion 43 mounted in suitable bearings in a housing 44. The latter (Figs. 2 and 4) is formed with trunnions 45 mounted in the bearings of a stand 46 and is formed with internal bearings, coaxial with the trunnions 45, for receiving a gear wheel 47 which meshes with the pinion 43. The gear wheel 47 also meshes with a pinion 48, which is secured upon the shaft 30 and is of the same pitch.

diameter as the pinions 29 on such shaft meshing with the racks of the bars 17 which actuate the inner side guide. The housing 44 has pivoted thereto, coaxially with the pinion 43, an enclosing guide member 49 through which the bar 41 passes and in which are mounted rolls 50 which bear upon the top of the bar 41 and maintain the rack 42 in proper mesh with the teeth of the pinion 43.

Considering the housing 44 as stationary, as will be the case when an adjustment merely of the side guide 20 is being made, it will be seen that, the peripheral speeds of the pinions 29, pinion 48, gear wheel 47 and pinion 43 being the same, the bar 41 will have a longitudinal movement which is the same as any that may be imparted to the bar 17. Thus during an adjustment of the inner side guide, no movement of the lifting fingers 21 relatively thereto will occur.

For moving the lifting fingers 21, in order to effect a tilting of the metal or a return of the lifting fingers, the housing 44 is rocked in its bearings in the stand 46, whereupon the pinion 43 has a planetary movement around the gear wheel 47 with a resulting movement of the bar 41 relative to the bar 17 and consequently a rocking of the shafts 37 in one direction or the other to raise or lower the lifting fingers 21. In order to effect the rocking movement of the housing 44 when desired, the latter is formed with a rearwardly extending ear 51 to which is pivoted the upper end of a connecting rod 52 the lower end of which is pivoted to the crank pin 53 of a crank disk 54 secured to a shaft 55 which is actuated through a suitable reduction unit 56 from a third electric motor, 57. By operating the motor 57, the housing 44 can be made to rock in one direction or the other in its bearings in the stand 46, with the result that the bar 41 is caused to move either forwardly or rearwardly in relation to the bar 17, with an accompanying raising or lowering of the lifting fingers 21.

In the operation of the device, when it is desired to shift the metal laterally with respect to the feed rolls 11, either or both of the motors 27, 32 are operated to move the side guides in the desired directions. When it is desired to turn the metal on edge, the motor 57 is operated to actuate the lifting fingers 21, and it will be observed that this actuation of the lifting fingers can be made to take place regardless of whether the inner side guide is at rest or in motion at the time.

The manipulator of my invention employs no rotating or sliding parts supported in bearings requiring particular accuracy of alignment; and the construction, further, is such that any wear of one element which may take place is not likely to affect injuriously the operation of other elements.

For instance, wear of the bars 17 or the rollers upon which such bars are supported could not injuriously affect the operation of the tilting element, comprised by the bar 41, shafts 37, etc.

Another advantage of my improved manipulator is that all of its parts move in planes which are parallel with one another, no instrumentalities being employed for converting motion in one plane into motion in a plane at an angle thereto. In addition, the manipulator is of an exceptionally simple and economical construction and can be installed cheaply.

In Fig. 5 there is shown a modified means for actuating the lifting fingers 21. According to this construction a link 60 is pivotally mounted upon a standard 61 extending upward from the foundation. Rotatably mounted in the link 60 is a sheave 62 around which passes a flexible cable 63 one end of which is wound upon a drum 64. This drum is secured to the shaft 30 and is of a diameter which, taking into consideration the diameter of the cable 63, corresponds with the pitch diameter of the pinions 29 which actuate the bars 17. The other end of the cable 63 is secured to a lever 64 which is connected between the ends of the shafts 37. By this construction, as the bars 17 and inner side guide move in one direction or the other, the cable 63 will be paid out, or taken up, to a corresponding extent; so that the lifting fingers 21 will remain stationary with respect to the inner side guide. In order to effect independent movement of the lifting fingers, the link 60 has pivoted to its upper end a connecting rod 65, one end of this rod being pivoted to a crank 67 secured upon the shaft of a motor 68. When the motor 68 is operated, the link 60 will be caused to rock in one direction or the other, thereby to pull upon the cable 63, raising the lifting fingers 21, or to slacken such cable, allowing the lifting fingers to descend by reason of their weight.

I claim:

1. A manipulator comprising a movable side guide, a device for moving the same, a tilting element associated with said side guide, and means for actuating said tilting element, said actuating means including a rotatable member cooperatively associated with said device so as to be rotated at a peripheral speed substantially the same as the speed of movement of said side guide, and means for operating said rotatable member to actuate said tilting element.

2. A manipulator comprising a movable side guide, a device for moving the same, a tilting element associated with said side guide, and means for actuating said tilting element, said actuating means including a normally stationary rotatable member cooperatively associated with said driving device

- so as to be rotated at a peripheral speed substantially the same as the speed of movement of said side guide, and means for bodily moving said member, thereby to actuate said tilting element.
3. A manipulator comprising a movable side guide, a tilting element associated therewith, an actuating member for said tilting element, a device for operating said actuating member, means for operating said device during movement of said side guide to cause said actuating member to move through distances the same as moved through by said side guide, thereby to maintain said tilting element substantially stationary with respect to said side guide during movements of the latter, and means for operating said device to cause relative movement between said actuating member and said side guide, thereby to actuate said tilting element.
4. A manipulator comprising a movable side guide, a tilting element associated therewith, a member for actuating said tilting element, a normally stationary device associated with said member for moving the latter, means for operating said device during movements of said side guide to move said member at substantially the speed of movement of said side guide, and means for operating said device to move said member relatively to said side guide, thereby to actuate said tilting element.
5. A manipulator comprising a movable side guide, a tilting element associated therewith, a member for actuating said tilting element, a normally stationary rotatable member associated with said actuating member to move the latter, means for rotating said rotatable member to cause said actuating member to move at substantially the speed of movement of said side guide, and means for bodily moving said rotatable member, thereby to actuate said tilting element.
6. A manipulator comprising a movable side guide, means for moving the same, a tilting element associated with said side guide, a member for actuating said tilting element, a rotatable member associated with said actuating member for moving the latter, connection means between said rotatable member and said side guide moving means to cause said rotatable member to move said actuating member at a speed proportionate to the speed of movement of said side guide, and means for operating said rotatable member to effect relative movement between said actuating member and said side guide, thereby to actuate said tilting element.
7. A manipulator comprising a movable side guide, means for moving the same, a tilting element associated with said side guide, a member for actuating said tilting element, a normally stationary rotatable member associated with said actuating member for moving the latter, connection means between said rotatable member and said side guide moving means to cause said rotatable member to move said actuating member at a speed proportionate to the speed of movement of said side guide, and means for operating said rotatable member to effect relative movement between said actuating member and said side guide, thereby to actuate said tilting element.
- member associated with said actuating member for moving the latter, connection means between said rotatable member and said side guide moving means to cause said rotatable member to move said actuating member at a speed proportionate to the speed of movement of said side guide, and means for bodily moving said rotatable member, whereby said tilting element is actuated.
8. A manipulator comprising a movable side guide, rotary means for moving the same, a tilting element associated with said side guide, rotary actuating means for said tilting element, connection means between said first and second named rotary means for causing them to move at corresponding peripheral speeds, and separate means for operating said rotary actuating means to actuate said tilting element.
9. A manipulator comprising a side guide, a rack associated therewith, a pinion for moving said rack, a tilting element associated with said side guide, a normally stationary rotatable member for actuating said tilting element, connection means between said pinion and said rotatable member for causing the latter to rotate at a peripheral speed corresponding to that of said pinion, and means for bodily moving said rotatable member, whereby said tilting element is actuated.
10. A manipulator comprising a side guide, a rotatable member for moving the same, a tilting element associated with said side guide, a stationary pivoted support, a rotatable member carried by said support for actuating said tilting element, gearing carried by said support and associated with said rotatable members to cause them to rotate at corresponding peripheral speeds, and means for rocking said support about its pivot, whereby said tilting element is actuated.
11. A manipulator comprising a side guide, a rotatable member for moving the same, a tilting element associated with said side guide, a stationary pivoted support, a gear wheel carried by said support coaxially with the pivot thereof, connection means whereby said gear wheel is driven by said rotatable member, a pinion carried by said support and disposed in planetary association with said gear wheel, connection means between said pinion and said tilting element, and means for moving said support about its pivot, whereby said tilting element is actuated.
12. A manipulator comprising a side guide, a rack for moving the same, a pinion for actuating said rack, a tilting element associated with said side guide, a pivoted support, a gear wheel associated with said support coaxially with the pivot thereof and having geared relation with said pinion to cause it to move at the same peripheral speed as the latter, a pinion carried by said

support in planetary association with said gear wheel, a rack meshing with said last-named pinion and connected with said tilting element to actuate the latter, and means for rocking said support about its pivot, whereby said tilting element is actuated.

13. A manipulator comprising a movable side guide, a tilting element associated therewith, a pulley mounted for bodily movement, flexible means passing over said pulley and connected with said tilting element, means for moving said flexible means to accord with movement of said side guide, and means for bodily moving said pulley thereby to actuate said tilting element through said flexible means.

14. A manipulator comprising a movable side guide, a tilting element associated therewith, a pulley mounted for bodily movement, a second pulley, flexible means passing over said first-named pulley connected with said tilting element and wound on said second-named pulley, means for rotating said second-named pulley at a speed to correspond with movement of said side guide, and means for bodily moving said first-named pulley thereby to actuate said tilting element through said flexible means.

In testimony whereof, I sign my name.

30 JOHN A. SMITMANS.
